UNITED STATES PATENT OFFICE.

JOHN B. HIRD, JR., OF SEATTLE, WASHINGTON, ASSIGNOR, BY DIRECT AND MESNE ASSIGNMENTS, TO HIRD-ANDERSON MACHINERY CO., A CORPORATION.

INTERNAL-COMBUSTION ENGINE.

Application filed September 5, 1924. Serial No. 736,005.

This invention relates to improvements in two cycle internal combustion engines of the type embodying two piston members reciprocable one within the other and the objects 5 of this invention are to simplify and cheapen the construction and increase the efficiency of engines of this nature.

More specific objects are to provide an engine having improved means for storing 10 and compressing a fuel charge; to provide an improved form of sleeve piston having an eccentrically disposed enlarged portion on the bottom end which affords an advantageous connection with a connecting rod, 15 prevents turning of the sleeve piston in the cylinder and makes it possible to use one connecting rod only on said sleeve piston; to provide means for independently counter-balancing each the sleeve piston and the 20 usual piston effecting a saving in weight and producing an engine that runs very smoothly; and to provide efficient lubricating means that will insure thorough and efficient lubrication of all working parts.

25 Other and more specific objects will be apparent from the following description taken in connection with the accompanying drawings.

In the drawings, Figure 1 is a vertical 30 sectional view of an engine constructed in accordance with this invention.

Fig. 2 is a vertical section of the same substantially on broken line 2-2 of Fig. 1, parts being shown in elevation.

35 Fig. 3 is a fragmentary sectional view showing the piston members in an opposite position from that in which they are shown in Figs. 1 and 2.

Fig. 4 is another fragmentary sectional 40 view illustrating the relation between the fuel inlet and exhaust ports in opening and closing.

Fig. 5 is a view in cross section on broken 45 line 5-5 of Fig. 3 showing the eccentric member on the lower end of the sleeve piston.

Referring to the drawings, throughout 50 which like reference numerals designate like parts, 6 designates a base, supporting an upper frame 7 whereon is mounted an engine cylinder 8. The cylinder 8 is provided with the usual water jacket spaces 10 through which cooling agent may be circulated by communicating pipes 11 and 12 and is further provided with a cylinder head or cap 55

13 having a suction operated valve 14 normally urged into a closed position by a spring 15 for controlling the admission of gasified fuel from a carburetor 16.

The cylinder 8 is provided at the bottom 60 end with an enlarged portion 17 arranged eccentrically thereto as shown in Figs. 1 and 5 and said cylinder is adapted for the reception of reciprocable tubular piston 18 hereinafter termed a sleeve piston. 65

The sleeve piston 18 is provided at its bottom end with a larger eccentric portion 20 that fits into and reciprocates within the large bottom portion 17 of the cylinder 8. A piston ring 22 is provided near the top of 70 the sleeve piston 18 and another piston ring 21 is provided near the top end of the enlarged part 17 of said sleeve. The sleeve piston 18 is provided with a piston head 23 which is threaded thereto to make the same 75 adjustable if desired. The interior of the sleeve piston 18 is accurately bored for the reception of a reciprocable piston 24 of the usual type.

A crank shaft 25 is rotatably mounted in 80 bearings 26 and 27 in the base 6 and upper housing 7 and is provided with two diametrically opposite cranks 28 and 30 connected respectively by connecting rods 31 and 32 with the sleeve piston 18 and the 85 other piston 24. The eccentricity of the enlarged bottom portion 20 of sleeve piston 18 makes it possible to connect the upper end of connecting rod 31 with the interior of said enlarged portion 20 instead of connecting 90 the same to the outside of the sleeve piston as is usually done in engines of this type. The eccentricity of portion 20 also prevents rotation or turning of the sleeve piston in the cylinder and makes possible 95 the use of a single connecting rod for the sleeve piston instead of requiring two oppositely disposed connecting rods to balance the side thrust as are commonly required in engines of this type. This form of connection obviates the necessity of allowing the 100 sleeve piston to project at all times below the end of the cylinder in which it reciprocates and makes possible a shortening of the engine and a saving of space and weight. 105

The sleeve piston 18 is provided near its upper end just below the head 23 with a fuel inlet port 33 that is arranged to register with a port 34 in the wall of cylinder 8 when sleeve piston 18 is in the uppermost 110

position to permit gasified fuel to enter said sleeve piston. Another port 35 is provided in the wall of sleeve piston 18 near the upper end and is arranged to register with a spark plug 36 when the sleeve piston 18 reaches substantially its lowermost position as shown in Fig. 3 so that the compressed fuel charge may be fired by the spark plug.

Exhaust ports 37 are provided in the walls 10 of the sleeve piston 18 toward the lower end thereof and are adapted to lap over and register with exhaust ports 38 in the walls of cylinder 8 when the sleeve piston is at, or near, the upper limit of its stroke.

15 Gasified fuel for combustion purposes is drawn past valve 14 into the space above the sleeve piston 18 thence passes through ports 40 into passageway 41 which communicates with chamber 42 and with the upper end of 20 the enlarged lower end 17 of the cylinder. The side walls of chamber 42 are formed of a rectangular frame 43 supported on stud bolts 44 and having a cover plate 45. The required size of chamber 42 may be obtained by varying the depth of frame 43. This may be done by substituting for one frame a frame of another size or by planing down a frame 43 as the tests of an 25 engine are made until the proper adjustment of chamber 42 is obtained.

An oil pump 46 is provided within the lowermost portion of the crank case 6 and is arranged to be driven by skew gears 47 to provide forced lubrication for the various 30 working parts. Oil from pump 46 is forced upwardly through passageway 48, Fig. 2, thence through pipes 52 and 53 to bearings 27 and 26 respectively, thence through bores 54 and 55 to the connecting rod bearings on 35 cranks 30 and 28, thence through bores or conduits 56 and 57 in connecting rods 32 and 31 to the wrist pin bearings in piston 24 and enlarged sleeve portion 20. A vertical pipe 58 connected with conduit pipe 52 40 enters cylinder 8 at a point just below the lowermost limit of the movement of piston ring 22 on sleeve 18 and supplies lubricant for the sleeve piston. A shallow spiral groove 59 in the sleeve piston insures the 45 proper downward feed of the oil thus supplied.

A check valve 49 resiliently and adjustably supported by a spring 50 is arranged to be opened by excess oil pressure to permit 50 an overflow through port 51 in case more oil than is necessary is supplied by pump 46.

The usual fly wheel 60 is provided on crank shaft 25.

60 A counterweight 61 is provided on crank shaft 25 at a point diametrically opposite connecting rod bearing of crank 28 to counterbalance as nearly as possible the movement of the sleeve piston and another counterweight 62 is provided on the crank shaft 65 25 diametrically opposite connecting rod

bearing of crank 30 to similarly counterbalance the movement of piston 24 and rod 32.

The counterweights 61 and 62 are shown to be secured to the crank shaft by U bolts 63 but obviously may be integral with said 70 crank shaft or may be otherwise supported thereon.

These counterweights for independently counterbalancing piston 24 and sleeve 18 are important features which permit the use of a lighter fly wheel and the use of a lighter frame structure for the engine, make the engine run more smoothly and generally increase the efficiency and reduce the vibration 75 of the same.

In operation when the sleeve piston 18 is in the uppermost position and the piston 24 is in the lowermost position the inlet and exhaust ports will both be wide open and gasified fuel under pressure will be rushing 80 into the sleeve piston and driving out the exhaust gases. As the sleeve piston 18 begins to move down and the inner piston 24 begins to move up the inlet port 34 will first be closed as shown in Fig. 3 and the exhaust 85 will continue until the piston 24 laps and closes the port 37, whereupon compression of the fuel gases will begin and will continue until the pistons 16 and 24 reach the other extreme position shown in Fig. 3 at 90 which time the port 35 will uncover the spark plug 36 and the charge will be fired. Timing mechanism 65 will be used to control the delivery of the spark which may be delivered just before the point of maximum 95 compression is reached. The gasified fuel, having entered under compression will be highly compressed at the time of the explosion and the sleeve piston 16 and piston 24 will be driven apart with great force 100 causing an upward pull on the crank 28 and a downward thrust on the crank 32, said pull and thrust jointly tending to impart a powerful torque to the crank shaft 25 and at 105 the same time balancing each other in such a manner as to tend to eliminate vibration. 110

As the two pistons, in moving apart, approach their extreme positions the exhaust ports 37 will first be uncovered allowing exhaust to begin and the fuel inlet port 34 will then be uncovered allowing a charge of compressed fuel to rush in and crowd out the exhaust gases, the ports being arranged so that exhaust closes just before the fresh fuel begins to pass out of the exhaust ports. 115

When the pistons are in the outermost extreme position shown in Figs. 1 and 2 substantially all of the gasified fuel will be expelled by the enlarged lower end 20 of the sleeve piston from the chamber 17 and the major portion of the gasified fuel will be expelled from the upper end of the cylinder 8, but the fuel chamber 42 will always contain fuel. As soon as the sleeve piston 125 130 begins to move downwardly on the com-

pression stroke a suction will be produced in the upper end of cylinder 8 and in the upper portion of enlarged chamber 17 at the bottom of cylinder 8 thus drawing in 5 more fuel gas through carburetor 16, which fuel gas, thus drawn in, is compressed on the next upward stroke of sleeve piston 18 and admitted to the firing chamber as previously described.

10 In an engine of this type it is obviously necessary to attach the connecting rod to the sleeve piston at a point or points removed from the center. This makes it necessary either to balance the torque by 15 providing two oppositely disposed connecting rods, or by providing means for preventing the side thrust of one connecting rod from turning the piston or tending to turn the piston and thereby producing excessive 20 strain in the wrist pin and connecting rod. The eccentric portion 20 of this engine absolutely prevents rotation of the sleeve piston and makes it possible and practical to use a single rod and to connect the same within 25 the inside of extension 20 thereby eliminating parts and bearings and making the engine shorter and more compact.

The provision of the fuel pump formed by the enlarged chamber 17 and piston section 30 20 at the bottom of the cylinder is essential to supply enough fuel for the successful operation of the engine.

The engine may consist of as many cylinders as desired, only one cylinder being 35 herein shown to illustrate the invention.

Obviously many changes in the invention may be resorted to within the scope and spirit of the following claims.

I claim:

40 1. In an engine, a cylinder having, at the lower end, an eccentrically arranged chamber of larger diameter and having a fuel passageway connecting the upper end of the cylinder with the upper end of the enlarged 45 eccentric chamber, said cylinder having exhaust ports and having inlet ports that communicate with said fuel passageway, a tubular piston reciprocable in said cylinder and having an enlarged eccentrically disposed 50 bottom end reciprocable in said enlarged

piston chamber, said tubular piston having exhaust and inlet ports arranged to register with the respective exhaust and inlet ports of said cylinder and another piston reciprocable in said tubular piston. 55

2. In an engine, a cylinder having, at the lower end, an eccentrically arranged chamber of larger diameter and having a fuel passageway connecting the upper end of the cylinder with the upper end of the enlarged eccentric chamber, said cylinder having exhaust ports, and having inlet ports that communicate with said fuel passageway, a tubular piston reciprocable in said cylinder and having an enlarged eccentrically disposed bottom end reciprocable in said enlarged piston chamber, said tubular piston having exhaust and inlet ports arranged to register with the respective exhaust and inlet ports of said cylinder, another piston reciprocable 60 in said tubular piston, a crank shaft having two diametrically opposite cranks and two connecting rods connecting said cranks with said other piston and said sleeve piston respectively the point of connection of the 65 enlarged lower end of the sleeve piston with its crank being within said enlarged lower end. 70

3. In an engine, a cylinder having, at the lower end, an eccentrically arranged chamber of larger diameter and having a fuel passageway connecting the upper end of the cylinder with the upper end of the enlarged eccentric chamber, said cylinder having exhaust ports, and having inlet ports that 80 communicate with said fuel passageway, means forming a fuel chamber communicating with said fuel passageway, a tubular piston reciprocable in said cylinder and having an enlarged eccentrically disposed bottom end reciprocable in said enlarged piston chamber, said tubular piston having exhaust 85 and inlet ports arranged to register with the respective exhaust and inlet ports of said cylinder and another piston reciprocable in 90 said tubular piston. 95

The foregoing specification signed at Seattle, Washington, this 13th day of August, 1924.
